UNITED STATES PATENT OFFICE.

EDWARD F. DUDLEY, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

SHEET-PILE SUPPORT AND GUIDE.

Application filed March 3, 1921. Serial No. 449,509.

To all whom it may concern:

Be it known that I, EDWARD F. DUDLEY, a citizen of the United States, residing at Oak Park, in the county of Cook and State of Illinois, have invented certain new and useful Improvements in Sheet-Pile Supports and Guides, of which the following is a specification.

It is old in the art of printing-presses to support a pile or stack of paper or similar sheets and feed the support and sheets slowly upwardly to compensate for the successive removal of the uppermost sheets, thereby always maintaining the top of the pile at substantially an unvaried elevation and in co-operative relation with some kind of a sheet transportation or conveying appliance, such for example as a suction-feeder.

This invention relates to constructions which render possible and which facilitate the positioning of a new or reserve pile of sheets in the machine preliminary to the exhaustion of the active pile and ready to be shifted into operative position immediately upon the removal of the last sheet of the pile undergoing depletion.

The invention is particularly adapted for employment in the type of sheet feeding mechanism specified, but it is not necessarily limited or confined to such specific use, since its principles of construction and mode of operation with slight changes may be advantageously employed in sheet delivery mechanisms for printing-presses and similar machines.

Another feature of the invention resides in improved pile guides or gauges which are active through the full depth of the pile regardless of the original height of the latter.

In the accompanying drawings, forming a part of this specification, and throughout the several views of which like reference characters refer to the same parts, a preferred and desirable embodiment of the invention has been illustrated, and to such drawings reference should be had in con-

nection with the following detailed description of the construction and mode of operation of such device.

In this drawing:

Figure 1 is a plan view of the appliance;

Figure 2 is a front elevation of the same with parts broken away;

Figure 3 is a vertical cross-section on line 55 3-3 of Figure 1;

Figures 4 and 5 illustrate the details of construction of one of the sheet pile guides or gauges and its supporting block; and

Figures 6 and 7 indicate the manner of 60 supporting the pile-board on the upright conveyer-chains, Figure 7 being a bottom plan view of one of the supporting lugs for such board, which coacts with one of the sprocket-chains.

Referring to these drawings, it will be seen that the improved and novel appliance includes end frame members 11 and 12 (Figures 1 and 2) supporting in suitable bearings a revoluble, rear shaft 13 equipped with 70 a pair of sprocket-wheels 14 spaced apart a considerable distance and located near such frame portions.

These sprocket-wheels are fitted with a pair of coacting vertical sprocket-chains 15, 75 15 passing around sprocket-wheels 16, 16 on a shaft 17, parallel to and some distance below the upper shaft and revoluble in appropriate bearings in the frame.

At the front of the structure there is a 80 similar upper shaft 18 fitted with a pair of sprocket-wheels 19, 19 spaced apart on the shaft a distance slightly greater than that between the sprocket-wheels 14, 14 to permit the insertion and withdrawal of the 85 sheet pile supporting-boards as will be readily understood from the remainder of the construction.

In similar manner these latter sprocket-wheels are provided with upright, endless 90 sprocket-chains 21, 21 coacting with a pair of sprocket-wheels 22, 22 on a front lower shaft 23, appropriately journaled in the frame work.

These four upright chains or conveyers are adapted to support the board or boards carrying the pile or piles of paper sheets, and, to this end, the machine is supplied 5 with a plurality of such pile-boards 24, both views of Figure 2 and Figure 3 illustrating two of them, each having two rear outstanding supporting lugs or ears 25, 25 spaced apart the proper distance to fit into the 10 apertures of the back chains 15, 15 and having also two front projecting supporting ears or lugs 26, 26 spaced apart the correct amount to fit in the holes of the links of the forward chains 21, 21, the under face of 15 each of such projecting members being recessed as shown in Figures 6 and 7 to receive parts of the links and thus prevent unintentional dislodgment or displacement of the board.

It is, of course, necessary to operate such chains simultaneously and equally in small increments to compensate, by raising the board or table slowly and progressively, for the successive and steady removal of the 25 topmost sheets from the pile.

To this end an oscillatory drive-shaft 31, operated in any approved manner, is connected by a link 32 to a bell-crank 33 connected by a link 34 to a rock-arm 35 oscillatory on a properly journaled worm shaft 36 and equipped with a pawl 37 coacting with a ratchet-wheel 38 fixed to the shaft.

Obviously the oscillation of shaft 31 effects the small step by step movements of 30 shaft 36 and these are transmitted to the several sprocket-chains by worms 39 and 41 on shaft 36 meshing with worm-wheels 42 and 43, respectively, on the lower shafts 17 and 23.

To permit a more rapid hand-operated 40 actuation of the chains, as may be desired upon shifting into position a new pile of sheets to replace an exhausted one, shaft 36 is equipped with a normally-inactive handle 44 loose on the shaft and which may be operatively connected to the latter by moving it lengthwise thereon to cause a pin 45 projecting transversely from the shaft to fit in a notch or recess 46 of the handle hub.

The sprocket-chains are of sufficient 50 length so that when the stock of sheets on the upper board 24 nears exhaustion, a second supply board loaded with a new pile may be slipped in under the upper board and its supporting lugs or ears readily caused to engage and be sustained by the chain links.

When the last sheet has been taken from 60 the top board, the operator removes the latter, and by means of the handle 44 quickly and easily elevates the underlying pile into operative position.

By thus placing the new board and its pile in position before it is really needed,

the workman can save time in the replacement of piles or stacks of sheets and the machine can consequently be run with greater economy and efficiency.

Guides or gauges are required to keep the sheets of the pile in proper alignment or register and it is convenient to so construct them that they will automatically shift position and not interfere with the gradual rise of the pile supporting board while the sheets of the lower portion of the stack are being removed individually one 70 after the other.

As is clearly shown in Figures 1 and 3, the edges of the sheets toward the printing-press are kept in register by a pair of appropriately-mounted, upright guides 47 and 80 48, the position of which in no way conflicts with the upward travel of the pile supporting board or boards.

The opposite edges of the sheets are maintained in correct register by a pair of bent, 85 inclined guide-bars 49 and 51 each hinged at its upper end at 52 (Figure 5) to a bar 53 supported and adjustably slidable in a block 54 mounted and shiftable as to its position along a supporting bar 55 fastened 90 at its opposite ends to the frame of the appliance.

Element 54 has a thumb-screw 61 adapted to clamp the three parts 53, 54 and 55 rigidly together after they have been properly 95 adjusted.

As is shown in Figure 5 each gauge member 49 or 51 has a projecting pin 56 adapted to bear against an edge of a downwardly bent end 57 of bar 53 to limit the descent 100 of the gauge, whereby it will normally be in the inclined relation shown in Figure 2.

Supporting bar 55 also carries two other adjustable blocks 58, 59 on each of which a sloping or slanting gauge or guide 62 is directly hinged or pivoted and limited as to downward swinging by one of its end edges engaging beneath bar 55, as shown in Figure 3. One of such guide or gauge bars is used for each end of the pile.

When the sheet pile board approaches 110 its upper limit of travel to discharge in sequence the sheets forming the lower portion of its stack, it engages the lower ends of the several inclined pivoted pile guides or gauge bars and swings them gradually upwardly automatically, at the same time, however, permitting them to fully perform their functions until the last sheet is delivered.

Upon removal of such upper pile-board from the machine the gauge bars automatically rock down to the positions illustrated in the several figures, such downward swinging, of course, being limited by their 125 stop means heretofore described.

Obviously many slight mechanical changes may be made in the structure shown and described without departure from the spirit and scope of the invention, the underlying principles of which will be readily understood by those skilled in this art from the full and complete illustration and description hereby presented. By operating the chains so that they feed the boards downwardly instead of upwardly this appliance may be readily employed as a sheet delivery mechanism, whereby when one board has received a sufficient stack of the discharged sheets, a new one can be applied to the chains above it, after which the loaded board can be removed from the machine.

I claim:

1. In a paper-pile feeder of the character described, the combination of a pair of spaced upright endless conveyers, a second pair of upright endless conveyers spaced apart less than the distance between said first pair of conveyers, means to simultaneously operate said conveyers, and a paper-pile board demountably supported on said conveyers permitting the ready application of the board to and its removal from said conveyers, substantially as described.
2. In a paper-pile feeder of the character described, the combination of a pair of spaced upright endless conveyers, a second pair of upright endless conveyers spaced apart less than the distance between said first pair of conveyers, means to simulta-

neously operate said conveyers, and a plurality of paper-pile boards constructed to be simultaneously demountably supported each on all four of said conveyers permitting the ready application of either board to and its removal from said conveyers, substantially as described.

3. In a paper-pile feeder of the character described, the combination of a pair of spaced upright endless conveyers, a second pair of upright endless conveyers spaced apart less than the distance between said first pair of conveyers, power-operated means to actuate said conveyers, hand-operated means to actuate said conveyers, and a plurality of paper-pile boards constructed to be simultaneously demountably supported in vertically-spaced relation each on all four of said conveyers permitting the ready application of either board to and its removal from the conveyers, substantially as described.

4. In a paper-pile feeder of the character described, the combination of a support, a pair of rear spaced upright endless sprocket-chains, a pair of front upright endless sprocket-chains spaced apart a distance greater than that between said rear chains, sprocket-wheels for all of said chains, means to operate said sprocket-wheels and chains, and a paper pile board demountably supported on said chains by lugs on the board fitting in apertures of the links of said chains, substantially as described.

EDWARD F. DUDLEY.
